SUPERHEATER

Wilbur H. Armacost, New York, N. Y., assignor to
The Superheater Company, New York, N. Y.

Application November 25, 1938, Serial No. 242,364

5 Claims. (Cl. 122—480)

The present invention relates to boilers equipped with superheaters and particularly to improvements in means for bypassing part of the gases around the superheater to regulate the 5 final temperature of the superheated steam.

It has been found in vertical type water tube boilers having an upper and a lower drum connected by a bank of generating tubes with a superheater located in a down-pass, that a large 10 damper area is required to bypass 20 or 30% of the gases when the bypass damper is located a distance below the steam drum. An object of the present invention is to provide in such a boiler a damper controlled bypass so arranged 15 and located that the bypass area and the damper are not of unduly large size. A second object of the invention is to avoid increase in draft loss due to increased resistance to gas flow through the boiler as a result of the provision of a bypass. 20 Another object is to increase the mass flow of gases over the superheater with consequent greater heat absorption per unit of superheating surface.

The invention will best be understood upon 25 consideration of the following detailed description and appended claims when read in conjunction with the accompanying drawing in which the single figure is a diagrammatic elevational view, partly in section, of a vertical type water 30 tube boiler embodying the invention.

The boiler illustrated is of the vertical water tube type and comprises an upper steam drum 10 disposed above and interconnected with a water drum 11 by a generating bank 12 consisting of 35 tubes connecting into openings arranged in rows extending longitudinally of the drums with the rows spaced circumferentially of the drums. As shown, the boiler also includes another upper drum 13 connected to the water drum 11 by tubes 40 14 and to the steam drum 10 by tubes 15, 16. The generating bank 12 includes two baffle-supporting rows of tubes 20 and 21 which are spaced to form a gas pass within which a superheater is located. These tube rows are more closely positioned near the lower drum 11 so as to restrict or narrow the lower portion 22 of the gas pass, extending to and terminating at its outlet, as compared with the relatively wider upper portion 23 of the gas path extending from the entrance of the pass to the contiguous restricted portion 22.

On the tube rows 20 the baffling means 24 extends upwardly from the lower drum 11 and terminates at a point short of the steam drum 10 55 while the baffling means on the tubes of row 21

extend downwardly from the steam drum 10 and terminate short of the water drum 11. As one means for narrowing the lower portion of the gas pass and to form a by-pass, the lower portions 25 of some of the tubes in the row 21 are offset from the row in a direction towards the tube row 20 so that the lower portion 22 of the gas pass is narrowed or restricted as compared with its relatively wider upper portion 23. Superheating elements connected to headers 26 and 27 are so formed and arranged that a part 28 of the superheating elements are located in the wider portion 23 of the gas pass and a part 29 located in the narrowed portion 22 of the gas pass. The amount of superheating surface in the element parts 29 is that part which would determine the amount of steam temperature variation due to bypassing. The baffling on the lower offset parts 25 of some tubes in row 21 also forms one wall of the bypass around the elements 29. The lower parts 30 of other tubes in the row 21 are offset in the opposite direction so as to define a gas pass 31 aligned with the right-hand part of the wider portion 23 of the main gas pass and substantially parallel to the narrowed lower portion 22 of the gas pass. Baffling means 32 are provided on the tubes of the row 21 with parts 33 and 34 on the tube portions 23 and 30, respectively, defining the common wall of the lower portion 24 of the gas pass and the by-pass and the opposite wall of the bypass 31.

An opening controlled by a damper 35 is provided in the baffling 33 so that the flow of gases from the wider portion 25 of the gas pass into the bypass 30 may be regulated. It will be apparent that, if desired, the opening in the baffling 33 might be located substantially as shown and the damper 35 itself located at the lower portion of the bypass 31.

In the operation of the above arrangement 40 when the bypass damper 35 is opened to regulate superheat, the portion of the gases which are bypassed around the superheater elements 29 in the restricted portion 24 of the bypass flow to and through the bypass without a change 45 from the direction they follow in flowing through the wider portion 23 of the gas pass and in a direction substantially parallel to the flow of gases through the restricted portions 22 of the main gas path. Inasmuch as the gases are bypassed without a substantial change in the direction of gas flow no additional resistance is introduced to the flow of gases through the boiler such as ordinarily results from turning gases 50 through a bypass leading off from a main pass 55

at an abrupt angle at the point where the entrance to the bypass is located. Furthermore, in boilers having a pass where the gases enter from one side to flow along tubes therein the gases have a tendency to flow across the nearest parts of the superheater and along the inner or further baffle as this is ordinarily the path of least resistance. This fact is of advantage in the arrangement shown since the gases therefore naturally flow toward the bypass and additional draft is not required to induce flow through the bypass. The free cross-sectional area of the narrow portion 22 of the gas path is such that the gas velocities, when the bypass 31 is in use, are substantially the same as the gas velocities in the wider part 23 of the gas pass. This, also, favors the flow of gases through the bypass.

It should also be noted that no appreciable amount of heat is wasted when bypassing to regulate superheat because all of the gases pass over parts of the generating bank after leaving the superheater pass and bypass.

In addition, when operating the boiler shown without bypassing part of the gases, the restricted portion 22 at the lower and outer part of the gas pass has a tendency to draw the gases back across the superheater elements from the usual flow path between the inner parts of the superheater and the inner baffle wall. The gases are also speeded up when flowing through the restricted portion 22 due to the decreased area so that a greater mass flow over the part 29 of the superheater, and a consequently greater heat absorption results.

33 While the restricted part 22 of the gas pass and the bypass 31 might be located near the upper drum with the wider portion 23 of the gas pass near the lower drum, the arrangement shown in the drawing is preferred since, for one thing, the damper 35 is located in a cooler zone because the bypassed gases have already been partially cooled in passing over the superheating elements 28 in the wider portion of the gas pass before reaching the damper 35. It will also be apparent that other changes and variations may be made without departing from the invention as disclosed herein. Accordingly it is desired and intended to include such variations and changes within the scope of the appended claims.

50 What I claim is:

1. In a vertical type water tube boiler having an upper and a lower drum interconnected by a bank of generating tubes; baffle means forming a gas pass within said bank having a portion beginning at the entrance to said pass that is wider than a contiguous portion terminating at the exit from said pass, the flow of gases through said pass being in a direction generally axial of the tubes of said bank; superheater elements located in the relatively wide portion of said gas pass and occupying substantially the entire space between said baffle means; superheater elements in the narrow portion of said gas pass; means forming a bypass generally parallel to the narrow portion of said gas pass and aligned with part of the wider portion of said gas pass; and damper means controlling the flow of gases from said wider portion of said gas path through said bypass, whereby gases may be bypassed around the superheater elements located in said narrow portion of said gas pass without substantially changing the direction of gas flow.

2. A vertical type water-tube boiler having an upper and a lower drum interconnected by a bank of generating tubes that includes two parallel,

baffle-supporting tube rows spaced to form a pass through which gases flow in a direction generally axial to the tubes in which a superheater may be mounted, parts of said tube rows that are located adjacent one drum being more closely positioned in parallel relation than parts adjacent the other drum to restrict or narrow said pass adjacent said one drum; superheater elements located in the relatively wide portion of said pass and occupying substantially the entire space between said tube rows; superheater elements in said restricted portion of said gas pass; means forming a by-pass that is aligned with and forming a continuation of part of the relatively wide portion of said gas pass and substantially parallel to the restricted portion thereof; and a damper controlling gas flow from said relatively wide portion of said gas pass through said bypass, whereby gases after flowing over the superheater elements in the wider portion of said pass may be bypassed around the superheater elements in the restricted portion of said gas path without substantially changing the direction of gas flow.

3. A vertical type water tube boiler having an upper and a lower drum interconnected by a bank of generating tubes that includes two baffle-supporting tube rows spaced to form a pass through which gases flow in a direction generally axial of the tubes and in which a superheater may be mounted, some tubes in one of said rows having parts adjacent one drum offset from said row in a direction to restrict or narrow said gas pass adjacent said drum and other tubes in said row having parts adjacent said drum offset in the opposite direction and so arranged as to form a bypass aligned with part of the relatively wide portion of said gas pass and substantially parallel to the restricted portion of said gas pass; superheater elements located in both the relatively wide and restricted portions of said gas pass; and a damper controlled outlet from said relatively wide portion of said gas pass to said bypass whereby gases may be bypassed around the superheater elements located in the restricted portion of said gas pass.

4. In a vertical type water tube boiler having an upper and a lower drum interconnected by a bank of generating tubes that includes two tube rows spaced to form a downpass through which gases flow in a direction generally axial of the tubes, at least some tubes in one of said rows having their lower portions offset toward the other of said tube rows to restrict or narrow the lower portion of said gas path that lies therebetween as compared with the relatively wider portion of the gas path lying between the upper parts of said tube rows; superheater elements located in both the relatively wide and restricted portions of said gas pass; baffling means on the tubes of said other row from the lower drum to a point short of the upper drum; baffling means on the tubes of said one row from said upper drum and along the offset portions of tubes thereof to a point short of the lower drum; other baffle means spaced from the offset baffle supporting parts of tubes in said one row and acting in conjunction therewith to form a bypass in alignment with part of the relatively wider portion of said gas pass and substantially parallel to the narrow portion thereof; and damper means controlling gas flow from said wider portion of said gas pass to said bypass for bypassing part of the gases around the superheater elements in the narrow portion of said gas pass without substantially changing the direction of gas flow.

5. In a vertical type water tube boiler having an upper and a lower drum interconnected by a bank of generating tubes that includes two tube rows spaced to form a downpass through which gases flow in a direction generally axial of the tubes, at least some tubes in one of said rows having their lower portions offset toward the other of said tube rows to restrict or narrow the lower portion of said gas path that lies therebetween as compared with the relatively wider portion of the gas path lying between the upper parts of said tube rows; other tubes in said one row having their lower portions offset in a direction away from said other row to define a bypass parallel to the restricted portion of said gas pass and in alignment with part of the

relatively wider portion thereof; superheater elements positioned in both the relatively wide and narrow portion of said gas pass; baffling means on the tubes of said other row from the lower drum to a part short of the upper drum; baffling means on the tubes of said one row from said upper drum and along the offset portions of said tubes to points short of the lower drum; and damper means controlling gas flow from said wider portion of said gas pass to said bypass 10 whereby gases may be bypassed around the superheater elements in the restricted portion of said gas path without substantially changing the direction of gas flow.
